(57) **CLAIM**

The ornamental design of a stool, as shown and described.

DESCRIPTION

FIG. 1 is a front side perspective view of a stool in accordance with the present invention;

FIG. 2 is a front side view thereof;

FIG. 3 is a right side view thereof;

FIG. 4 is a left side view thereof;

FIG. 5 is a bottom side view thereof; and,

FIG. 6 is a top view thereof.

The broken lines of the Figures show portions of the stool and form no part of the claimed design.
